VOLTAGE SELECTOR AND WIRING TERMINAL, PARTICULARLY FOR USE THEREWITH

Ernest Clark, Beeston, England, assignor to United-Carr Fastener Corporation, Cambridge, Mass., a corporation of Massachusetts

Application February 6, 1935, Serial No. 5,249

5 Claims. (Cl. 173—328)

The present invention relates to switches and more particularly to voltage selector switches, and aims generally to improve existing switches for that purpose.

5 One of the principal objects and advantages of the invention is to improve and simplify the construction of voltage selector switches to the end that a simple and inexpensive switch may be made to permit one or more electrically controlled devices to be selectively connected in circuit with different lines of varying voltages.

Other aims and advantages will be apparent from a consideration of the following detailed description of one preferred embodiment of the invention which is illustrated in the accompanying drawing.

In the drawing—

Fig. 1 is a front elevation of the improved switch;

20 Fig. 2 is a similar view with the cover panel removed;

Fig. 3 is a rear elevation of the switch;

Fig. 4 is an enlarged longitudinal sectional view taken on the line 4—4 of Fig. 1; and

25 Fig. 5 is a detail perspective view of one of the terminals according to one embodiment of the invention.

The particular embodiment of the invention illustrated in the drawing may advantageously comprise a base 1 of suitable insulating material, such as a fibrous or phenolic condensation insulating material to which is connected a plurality of lead-in terminals 2, each of which may carry a particular voltage different from the other. In the illustrated embodiment, three lead-in terminals 2 are shown, and by way of example they may carry voltages of 210, 230 and 250 respectively. The base 1 may also be provided with a plurality of take-off terminals 3, two of which are shown in the illustrated embodiment although it is apparent that one or more of these terminals may be used, each of the terminals 3 to be connected to an electrically operated device.

40 The base 1 may advantageously be mounted upon a panel 4 of suitable non-conducting material, and is advantageously spaced therefrom by means of insulating spaces 5 (see Fig. 4). On the side of the panel 4, opposite the base 1 there is a conductor strip or bus bar 6 conveniently formed of a thin ribbon of conducting material and electrically connected to the take-off terminals 3 in any suitable manner, but advantageously by means of fastening members 7 acting to secure the panel 4, contact strip 6, base 1 and terminals 3 in assembled relation. Conveniently

this fastening member may be in the form of a tubular fastening, such as a rivet, the ends of which are adapted to be upset over the contact strip 6 and terminal 3, and the spacers 5 may surround the rivet. Thus the base 1 with its associated parts and the panel 4 and the parts carried thereby are secured together in strong assembled relation.

5 The strip or bus bar 6 is preferably formed with a plurality of switch plug receiving apertures 8, one in registry with each of the lead-in terminals 2. Each of the terminals 2 is provided with a plug receiving socket 9 adapted to receive and hold the end of a removable switch plug 10, which preferably is formed with a conducting 15 stem 11 and a non-conducting handle portion 12.

In the form of invention illustrated in the drawing, the stem 11 of the switch plug is threaded to be screwed into a threaded opening in the plug receiving socket 9 so as to securely hold the 20 plug in place. However, my invention is not to be restricted to this particular form of plug as other forms of a plug or jack engaging a resilient socket 9 may be used satisfactorily.

25 As will be apparent when the plug 10 is inserted in any one of the openings 9, electrical connection is made between the registering lead-in terminal 2 and the take-off terminal 3 through the conducting stem 11 of the plug and the conductor strip 6. In this manner the take-off terminals 30 3 may be connected in circuit with the lead-in terminal carrying the desired voltage. Advantageously the panel member may be covered by a cover panel 13 provided with a plurality of openings 14 in registry with the opening 9, and the 35 openings 14 may be sufficiently large to receive the shouldered stem 11 of the plug 10 so that good electrical contact may be made between the plug and conducting strip 6.

40 Either or both of the terminals 2 or 3 may conveniently be made in the form of wiring tabs as shown in Fig. 5, in which case they may be preferably stamped from a single piece of metal to provide a body 15 centrally apertured as at 16 having laterally extending wings 17 formed with 45 prongs 18 adapted to be bent into clenching engagement with the base or other support. An extension 19 apertured as at 20 provides a suitable means to which the conductor may be secured as by soldering.

50 It will be understood that the invention is not to be restricted to the form and construction shown and described above which is intended for illustrative purposes only, but that the invention may be embodied in other forms and arrange- 55

ments within the scope of the appended claims. Also, the invention is usable for switches having one or more lead-in terminals and one or more take-off terminals.

5. I claim:

1. A voltage selector switch comprising a relatively thin base of non-conducting material, a thin insulating panel superposed upon said base, a plurality of lead-in terminals carried by said base having a portion disposed between said base and said panel, at least one take-off terminal carried by said base, a conducting strip disposed on the other side of said panel from said base and fastening means for connecting said base, strip and panel together, means connecting said strip and take-off terminal in electrical contact and a removable switch plug for establishing electrical contact between said strip and one of said lead-in terminals.
2. A voltage selector switch comprising a narrow base of thin insulating material, a plurality of lead-in terminals and at least one take-off terminal, each of said terminals carried by said base, said lead-in terminals having plug-receiving portions, a conducting strip, a wide panel of thin insulating material interposed between said strip and lead-in terminals, said wide panel overlying the lateral edges of said base and said terminals except at the plug-receiving portions of said lead-in terminals, a fastening means for connecting said base, strip and panel together, a means permanently connecting said strip and take-off terminal in electrical contact and a removable switch plug for establishing electrical contact between said strip and lead-in terminals.
3. A voltage selector switch comprising a base of insulating material, a plurality of lead-in terminals carried by said base, said lead-in terminals comprising a body portion and a tab projecting laterally from said body portion in substantially

parallel relation to said base and adapted for connection to an electrical conductor, a take-off terminal carried by said base and having a wire-receiving tab extending in substantially the direction of the tabs of said lead-in terminals, a conducting strip normally insulated from said lead-in terminals but in electrical contact with said take-off terminal, and means for optionally establishing an electrical conducting connection between said strip and one of said lead-in terminals.

4. A voltage selector switch comprising a thin base of non-conducting material, a plurality of lead-in terminals, a plurality of take-off terminals, each of said terminals carried by said base and having a wire-receiving tab extending laterally beyond the edge of said base, a conducting strip, a thin insulating panel interposed between said strip and lead-in terminals, and means permanently connecting said strip and take-off terminals in electrical contact and providing the sole means for connecting said base, strip and panel together.

35

5. A voltage selector device of the class described comprising a thin base plate of insulating material, a number of independent contacts attached to said plate, each of said contacts having a wiring terminal and a connector-receiving portion, said terminal and said connector-receiving portion of each of said contacts being integral one with another, a second thin plate of insulating material covering said contacts except at the connector-receiving portions, a conductor strip superposed upon said second plate and having apertures in alignment with the connector-receiving portions and a removable connector for optionally establishing an electrical connection between said strip and one of said contact terminals.
